TABLE LAMP

Kurt Versen, Tenafly, N. J.

Application January 12, 1949, Serial No. 203

Term of patent 14 years

(Cl. D48—20)

To all whom it may concern:

Be it known that I, Kurt Versen, a citizen of the United States, residing at Tenafly, in the county of Bergen and State of New Jersey, have invented a new, original, and ornamental Design for Table Lamp, of which the following is a specification, reference being had to the accompanying drawing, forming part thereof.

In the drawing:

Fig. 1 is a side view of a table lamp showing my new design. Figure 2 is a top plan view of Fig. 1, and Figs. 3, 4, 5 are side views showing the shade and arm in differently adjusted positions.

I claim:

The ornamental design for a table lamp, substantially as shown.

KURT VERSEN,
